UNITED STATES PATENT OFFICE.

GEORGE L. DALE, OF NEWARK, NEW JERSEY.

SEPARATOR.

SPECIFICATION forming part of Letters Patent No. 451,918, dated May 12, 1891.

Application filed October 9, 1890. Serial No. 367,498. (No model.)

To all whom it may concern:

Be it known that I, GEORGE L. DALE, a citizen of the United States, residing at Newark, in the county of Essex and State of New Jersey, have invented certain new and useful Improvements in Separators; and I do hereby declare the following to be a full, clear, and exact description of the invention, such as will enable others skilled in the art to which it applies to make and use the same.

This invention relates to separators, the object of the invention being to dispense with all mechanical action and provide an apparatus through which the material to be operated upon will pass by gravity, and in so passing will be divided or separated.

To the end above named the invention consists, essentially, of a tube or conduit formed from wire bent to spiral form, all as will be hereinafter more fully explained, and specifically pointed out in the claims.

I have herein illustrated and described a form of separator particularly adapted for use as an ash-sifter; but I desire it to be distinctly understood that the same or slightly modified constructions could be used for the purpose of screening coal, sand, grain, &c. In fact, I desire it to be understood that the apparatus could be used in many ways that are not hereinafter specifically referred to.

Reference is to be had to the accompanying drawings, forming a part of this specification, in which similar figures of reference indicate corresponding parts in all the views.

Figure 1 is a perspective view of my improved separator, the step-like cover employed in connection with the cinder-receptacle being represented as it appears when open. Fig. 2 is a sectional view of the hopper and the upper portion of the cabinet. Fig. 3 is a rear view of the apparatus, the cabinet-door being open; and Fig. 4 is a central sectional elevation of the apparatus, the tube or conduit being merely outlined in this view.

In the drawings, 10 represents the cabinet, in the lower portion of which there is arranged an ash-receptacle 11 and a cinder-receptacle 12, such cinder-receptacle being normally closed by a step-like structure 13, that is hinged to the main body of the cabinet and arranged so that it may be thrown to the po-

sition in which it is shown in Fig. 1. In the upper portion of the cabinet I mount a hopper 14, the lower opening of which is at times closed by traps 15 and 15^a, that are hinged to the side walls of the hopper, while the upper opening of the hopper is closed by other traps 16 and 16^a, such traps being by preference hinged to the walls of the cabinet. The traps 15 and 16 are connected by a chain 17 and the traps 15^a and 16^a are connected by a light rod 18, the direct connection between the rod and the traps being established by pivot pins or bolts. Within the cabinet I mount what might be called a "tube" or "conduit" 20, that is made of wire bent to spiral form, the various convolutions lying close up the one against the other. The upper end of the tube or conduit 20 is connected to a spout 21, carried by the hopper 14, and the body of the tube or conduit is carried spirally about a central post or standard 22, the lower end of the conduit extending through an aperture 2, formed in the front wall of the cabinet, the arrangement being such that all material passing downward through the tube or conduit of a size such that it will not pass out through the spaces existing between the various convolutions formed in the wire from which the conduit is made will be delivered within the receptacle 12. In mounting the tube or conduit I prefer to impart a slight tension to the wire, as I find that by so doing the tube becomes more rigid.

In operation the traps 16 and 16^a are opened—that is, thrown to the position in which they are shown in Fig. 2—and as the said traps 16 and 16^a are so opened the traps 15 and 15^a will be carried upward to their closed positions, as represented in Fig. 2. If at this time the hopper 14 be filled with intermingled ashes and cinders, the combined mass will be upheld until the traps 16 and 16^a are moved to the position in which they are represented in Figs. 3 and 4. The closing of the traps 16 and 16^a permits the opening of the traps 15 and 15^a, and hence the material contained within the hopper is free to pass downward through the tube or conduit 20, and in so passing the ashes and finer particles will fall outward through the spaces existing between the various convolutions in

the wire which forms the conduit, and such finer particles will drop into the receptacle 11, said receptacle being by preference in the form of a drawer. The larger particles will 5 pass through the lower opening of the tube or conduit and into the receptacle 12.

If from any cause the material placed within the hopper 14 should jam and not fall freely downward, it may be loosened and started on 10 its descent by slightly raising and lowering the trap 16, which motion of the trap would draw the chain 17 upward and downward through the mass and tend to loosen it.

From the above description it will be seen 15 that the desired separation is brought about without the use of hand or mechanical agitators, and it will be understood that little or no dust can escape from the cabinet at the time the separation is going on.

20 As before stated, I prefer that the cover of the cinder-receptacle 12 should be a step-like structure, and in practice I prefer to form such structure with two treads, the idea being to enable the operator to easily deposit the 25 material to be operated upon within the hopper.

Having thus fully described my invention, what I claim as new, and desire to secure by Letters Patent, is—

1. In a separator, the combination, with a 30 central post or standard, of a conduit coiled about said post or standard and formed from spirally-bent wire.

2. In a separator, the combination, with a 35 conduit formed from spirally-bent wire, of a hopper and traps arranged close to the bottom of the hopper, other traps arranged to close the top of the hopper, and connections between the upper and lower traps.

3. In a separator, the combination, with a 40 conduit formed from spirally-bent wire, of a hopper, traps arranged to close the bottom of the hopper, other traps arranged to close the top of the hopper, and connections between the upper and lower traps, one of such connections being a chain.

4. A separator embodying a spirally-coiled conduit formed from spirally-bent wire.

5. A separator embodying a spirally-coiled 50 conduit formed from spirally-bent wire, the axis of the spiral formed by coiling the conduit being substantially vertical.

In testimony whereof I affix my signature in presence of two witnesses.

GEORGE L. DALE.
